UNITED STATES PATENT OFFICE.

JOSEPH DUFFY, OF LONDON, ENGLAND.

SQUEEGEE DEVICE FOR APPLYING LIQUIDS TO SURFACES.

Application filed July 11, 1927, Serial No. 204,976, and in Great Britain August 24, 1926.

This invention relates to a squeegee device for applying liquids to surfaces. The device is particularly useful for hot liquid bituminous compound used when laying street paving blocks and which has to be moved to and fro by hand over the blocks so as to enter the spaces between the sides and ends of the blocks and form a mastic filling.

10 According to the present invention the squeegee device, is of open frame or bottomless box-like form and the liquid material is poured into the box, which has one or more handles so that it can be moved to and 15 fro as required. It is preferable to provide the under edges of the frame or box with strips of resilient or pliable material such as india rubber, which may be arranged in single or multiple form on the said edges and 20 the box may be provided with a suitable cover, if desired.

Amongst the advantages of the squeegee according to this invention are that the liquid is held together and is not unduly 25 spread, such holding together keeping the liquid hot for a long time and the weight of the liquid is helpful in pressing it into the said spaces or crevices.

I will describe my invention with reference to the example shown in the accompanying drawings, wherein:-

Fig. 1 is a perspective illustration of a box squeegee constructed in accordance with the invention, and the views in Figs. 2 and 35 3, are fragmentary views of the lower portion of a wall of a box such as that shown in Fig. 1, to which a single strip (Fig. 2) of india rubber, or two strips (Fig. 3) of this material, have been applied.

40 Referring to Fig. 1, the receptacle comprises front, back and side walls *a*, *a* and side walls *b*, *b* strengthened at the corners *c* by angle plates *d*. A handle *e* is carried by a stirrup formed by members *f*, *f*, pivoted 45 to the lower edge of the receptacle by bolts *g*. India rubber strips *h* are attached to the lower edges of the walls and may be a single strip as shown at *h'* in Fig. 2, or may be of double form as that shown at *h''*, Fig. 50 3. The rubber or flexible strips are secured

within recesses formed in the lower edges of the sides of the box-like frame.

A suitable cover may be hinged or otherwise used in conjunction with the rectangular box-like receptacles having the squeegees. 55

In use, for roadways constructed of paving blocks the hot liquid compound is poured into the receptacle and the same moved to and fro over the surface to be treated, so that, partly due to the weight of 60 the liquid in the receptacle and partly to the action of the flexible strips on the lower edges of the receptacle, and partly to the good retention of the heat by the mass, the liquid penetrates into the crevices between 65 the paving blocks in a highly efficient manner.

I have shown a rectangular receptacle for the hot bitumen compound but any other 70 convenient box-like shape which is bottomless may be employed and other constructional details of the box may vary as desired, as the flexible strips may be otherwise attached to the lower edges of the rectangular frame to project beyond said lower edges 75 and form a support for the aforesaid receptacle.

What I claim is:-

1. A squeegee for applying liquids to surfaces, more particularly road surfaces, comprising a substantially rectangular frame adapted to receive the liquid, a stirrup member pivoted to and adapted to be swung over the frame and carrying a handle and strips of resilient material such as india rubber 80 provided at each of the under edges of the frame.

2. A device of the character and for the purpose set forth comprising an open bottom frame, the lower edges of each of the 90 sides and ends having attached thereto strips of resilient material which project beyond the lower edges of the receptacle, the front and rear strips serving as spreaders when the receptacle contains fluid bitumen, 95 which material is spread upon a surface by a reciprocating movement of the frame.

3. A device for applying liquid bituminous material to road surfaces comprising a bottomless rectangular receptacle, resilient 100

strips attached to each of the lower edges of the receptacle and projecting beyond said edges, and a handle secured to the sides of the frame pivotally, the connecting means being adjacent to the lower edge of the receptacle.

4. A device for applying a surface to roadbeds comprising a bottomless receptacle

which is adapted to contain fluid surfacing material, the lower edges of the receptacle having attached thereto parallel resilient strips which extend below the front and rear lower edges of the frame and serve as spreaders when the receptacle is moved.

In testimony whereof I affix my signature.

JOSEPH DUFFY.
